DESIGN FOR A PRESSURE COOKER

Herbert E. Brannon, Dryden, Mich.; Charles W. Hayner, administrator of said Herbert E. Brannon, deceased

Application January 18, 1946, Serial No. 125,689

Term of patent 7 years

(Cl. D44—1)

To all whom it may concern:

Be it known that I, Herbert E. Brannon, a citizen of the United States, residing at Dryden, in the county of Lapeer and State of Michigan, have invented a new, original, and ornamental Design for a Pressure Cooker, of which the following is a specification, reference being had to the accompanying drawings, forming a part thereof.

In the drawings:

Figure 1 is a top plan view of a pressure cooker embodying my design; and

Figure 2 is a side view of the pressure cooker shown in Figure 1.

I claim:

The ornamental design for a pressure cooker, substantially as shown.

HERBERT E. BRANNON.
